HINGE PLATE RECESSING DEVICE
John Macala, Box 111, Kamsack, Saskatchewan, Canada
Filed Jan. 10, 1966, Ser. No. 519,713
1 Claim. (Cl. 145—60.5)

ABSTRACT OF THE DISCLOSURE

A casing containing a slidable frame which carries a set of geared together shafts equipped with cutters. The casing has a bottom wall with an opening through which the cutters are projected to an operative position when the frame is lowered in the casing, the frame being biased upwardly by springs. Adjustable stop elements on the frame are engageable with the bottom wall of the casing to limit the extent of projection of the cutters from the casing when the frame is lowered.

My invention relates to new and useful improvements in hinge plate drills.

Normal hinge plates used on doors and the like comprise a pair of substantially rectangular plates hinged together. It is conventional to recess these hinge plates, one upon the door edge and the other upon the door jamb so that the surfaces of the hinge plates are flush with the wood surfaces.

It is usual to chisel out the rectangular recess of a predetermined depth controlled by the thickness of the hinge plates and then to set the hinge plates within this recess. However, it will be appreciated that it is difficult to chisel out these rectangular recesses and to obtain a relatively even depth without some considerable time and care being expended.

I have overcome these disadvantages attendant upon the fitting of conventional hinges by providing a hinge plate which is curved at the ends and also which may be curved along one edge thereof, said curves having a fixed radius equal to the radius of action of the drill machine used.

By a provision of these novel hinge plates, I can utilize a multiple drill assembly to drill a plurality of overlapping, partially circular recesses within the edge of the door or door jamb, said recesses having a predetermined set depth. The drilling device may be powered by a hand drill, an electric drill, or an integral source of power as desired.

Therefore in setting the hinge plates, all that is necessary is to apply the drill assembly to the door edge or door jamb, rotate the drill and press downwardly until the limit controlled by the device is reached, whereupon the hinge plate may be set in and screwed to the door jamb and door edge thus saving many hours of labour in the fitting of a door to a door frame.

The principal object and essence of the device is therefore to provide a drilling assembly of the character herewithin described which enables a plurality of overlapping partially circular recesses to be formed within a door edge or door jamb, the contours of which are equal to the contours of the hinge plates.

Another object of the invention is to provide a device of the character herewithin described in which the recesses are positioned correctly with reference to the edge of the door or the door jamb thus eliminating any measurement prior to drilling.

Yet another object of the invention is to provide a device of the character herewithin described in which the depth of penetration of the drill may be controlled to suit the varying thicknesses of hinges normally used.

Still a further object of the invention is to provide a device of the character herewithin described in which the drill bits are normally in the uppermost position until pressure is applied against the device thus making the device safe in use.

2

With the foregoing in view, and all those objects, purposes, or advantages which may become apparent from consideration of this disclosure and specification, the present invention consists of the inventive concept embodied in the method, process, construction, arrangement of parts, or new use of the same, as herein particularly exemplified in one or more specific embodiments of such concept, reference being had to the accompanying figures in which:

FIGURE 1 is a plan view of one configuration of hinge plate used with my device.

FIGURE 2 is a plan view of an alternate configuration of hinge plate which may be used with my device.

FIGURE 3 is an end view of the device.

FIGURE 4 is a front view thereof.

FIGURE 5 is an underside view thereof.

FIGURE 6 is an enlarged sectional elevation with the front of the casing removed.

In the drawings like characters of reference indicate corresponding parts in the different figures.

Proceeding first to describe the hinge configuration, reference character 10 illustrates one half of a butt hinge, 11 indicating the hinge line and it will be understood that both halves are similar.

25 The rear side 12 of this hinge plate is provided with a perimetrical configuration comprising the intersecting arcs 13, 14 and 15 of three circles having similar radii and this hinge plate 10 is shown in dotted line in FIGURE 1. The solid lines 16, 17 and 18 define the boundaries of the intersecting recesses formed by the drilling device so that the hinge plate nests within the formed recess and may be screwed thereto.

FIGURE 2 shows an alternative configuration of a hinge plate 19 in which the ends 20 of the rear edge are arcs of circles having similar radii, the edge 21 being straight and tangential to these arcs. If this construction of hinge plate is utilized, then the portions shown in cross hatch in FIGURE 2 and identified by the reference character 22 have to be chiselled out after the recesses are formed. Once again the hinge plate nests within the formed recess and may be screwed thereto.

The device collectively designated 23 is utilized to form the recesses in the door jamb or door edge 24 hereinbefore described.

45 In detail, it consists of a guide casing collectively designated 25 having a front wall 26, end walls 27 and a rear wall (not illustrated) all of which form a hollow substantially rectangular configurated casing.

The upper side 28 of this casing is open and the lower side 29 is provided with a centrally located opening 30 having ends 31 which are arcs of circles of equal radii and sides 32 which are tangential to these arcs (see FIGURE 5). Situated within this casing is a drill assembly collectively designated 33. This drill assembly is carried by a frame consisting of a substantially rectangular upper plate 34 and a similar lower plate 35, said plate being maintained in spaced and parallel relationship by means of sides 36, the plates 34 and 35 and the sides 36 being secured together to form an integral unit.

60 This integral unit is adapted to reciprocate vertically within the guide casing 23 and springs 37 react between the lower plate 35 and the lower side 29 of the guide casing and normally maintain the drill assembly 33 in the uppermost position shown in FIGURE 6.

A main drive shaft 38 is journalled for rotation vertically within bearings 39 upon plates 34 and 35 and a pair of secondary drive shafts 40 are also journalled for vertical rotation within plates 34 and 35, bearings 39 being provided for this purpose so that the three shafts are in spaced and parallel relationship, there being a secondary shaft 40 upon each side of the main shaft 38.

Gears 41 are secured to the shafts and engage one another so that rotation of the main drive shaft 38 also rotates the secondary drive shafts 40.

Secured to the lower ends 42 of the secondary drive shafts and to the lower end 43 of the main drive shaft are blade type cutters 44. These cutters are vertically situated planar strips having sharpened lower edges 45, central guide points 46, and outer perimeter cutters 47. When the cutter element 44 secured to the main drive shaft 38 is aligned with the longitudinal axis of the device as shown in FIGURE 6, the cutters 44 secured to the secondary shafts 40 are situated at right angles thereto. The shafts 40 are situated so that the radii of action of the cutter elements overlap one another as shown in dotted line in FIGURE 5, reference character 47 indicating this overlapping relationship and it is this overlapping relationship which gives the required overlapping relationship of the circular recesses; formed within the door edge 24 or the door jamb (not illustrated).

In operation, a hand drill or electric drill (not illustrated) is secured to the extending portion 48 of the main drive shaft and the casing is placed upon the edge of the door 24. In this connection a downwardly extending flange 49 is formed as an extension of the rear wall of the casing and this flange engages the side 50 of the door thus positioning the cutters in the correct relationship.

The source of power is caused to rotate the drive shaft 38 and the gears rotate the secondary shafts 40. Downward pressure is applied to the shaft 38 by the source of power thus moving the entire drill assembly 33 downwardly against pressure of springs 37 so that the cutters 44 extend below the lower side 29 of the casing and engage the edge of the door. The rotating drills cut the recesses and continued downward pressure causes the drill assembly to move downwardly until adjustable stops 51 extending from the lower plate 35, strike the bottom plate 29 of the casing. Depending upon the adjustment of these stops 51, the depth of the recesses cut by the cutters is controlled.

As soon as the pressure is released, springs 37 return the drill assembly to the uppermost position shown in FIGURE 6 with the cutter elements 44 shrouded by the bottom plate 29 and thus in a safe condition.

It is desirable that the width of the ends 27 of the casing be such that the lower side 51 of the front of the casing is engageable with the door jamb stop strip (not illustrated) which also positions the cutters in the correct position.

It will therefore be seen that the device can be utilized to cut both the recesses within the edge of the door and within the door jamb with no measurements being required except for vertical positioning.

Since various modifications can be made to the invention herein described within the scope of the inventive concept disclosed, it is not intended that protection of the said invention should be interpreted as restricted to the modification or modifications or known parts of such concept as have been particularly described, defined, or exemplified, since this disclosure is intended to explain the construction and operation of such concept, and not for the purpose of limiting protection to any specific embodiment or details thereof.

What I claim as my invention is:

1. In a recessing device for hinge plates, the combination of an elongated casing including a bottom wall formed with an elongated opening, a guide flange rigid with said casing and projecting downwardly below said bottom wall for coaction with the bottom wall in locating said casing on a piece of work, a frame slidably positioned in said casing for raising and lowering movement relative to the casing, compression springs reacting between said frame and said bottom wall for biasing the frame to its raised position, a set of vertical shafts rotatably mounted in said frame and geared together for simultaneous rotation, a set of cutters secured to the lower ends of the respective shafts and having work engaging lower cutting edges disposed in a common plane, and vertically adjustable stop elements depending from said frame and engageable with said bottom wall, said cutters being disposed in said casing when said frame is in its raised position but being projectable downwardly through said bottom wall opening to a predetermined extent with respect to said bottom wall as limited by engagement of said stop elements with the bottom wall when said frame is lowered.
